US00D584348S

(12) **United States Design Patent**
Boo et al.

(10) **Patent No.:** **US D584,348 S**
(45) **Date of Patent:** **** Jan. 6, 2009**

(54) **COLOR LASER PRINTER**

(75) Inventors: **Min-Hyoung Boo**, Seoul (KR); **Hee-Yul Kim**, Kyunggi-do (KR); **Byeong-Yong Song**, Kyunggi-do (KR); **Yun-Gi Hong**, Kyunggi-do (KR)

(73) Assignee: **Samsung Electronics Co., Ltd.**, Kyunggi-do (KR)

(**) Term: **14 Years**

(21) Appl. No.: **29/293,253**

(22) Filed: **Nov. 13, 2007**

(51) **LOC (9) Cl.** **14-02**

(52) **U.S. Cl.** **D18/55**

(58) **Field of Classification Search** **D18/36-39, D18/50, 54, 54.1, 55; D14/420-425, 462-470; 400/613, 613.1-613.4, 690.1-690.4, 691-694**

(57) **CLAIM**

The ornamental design for a color laser printer, as shown and described.

DESCRIPTION

FIG. 1 is a top front perspective view of a color laser printer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
